PROCESS AND APPARATUS FOR LOCALLY ANNEALING METAL PLATES.

Application filed October 22, 1920. Serial No. 418,709.

To all whom it may concern:

Be it known that we, REUBEN STANLEY SMITH and RICHARD STRESAU, citizens of the United States, and residing, respectively, in the cities of Milwaukee and Wauwautosa, county of Milwaukee and State of Wisconsin, have invented certain new and useful Improvements in Processes and Apparatus for Locally Annealing Metal Plates (Case #168); and we do declare the following to be a clear, exact, and complete description thereof, such as will enable others skilled in the art to which the invention pertains to make and use the same, reference being had to the accompanying drawing as showing one form of apparatus in which the invention has been embodied and by means of which the process may be reduced to practice.

Our invention relates to a process and apparatus for annealing metal plates, and, without limiting the uses of the invention, we may state that it is particularly designed for annealing the concave marginal portions of the sheet metal blanks used in constructing the curved side bars and cross bars of an automobile frame.

The present invention relates to an improvement in the process of local annealing disclosed in application Serial #381,876, filed May 17, 1920, by R. Stanley Smith, one of the parties hereto, and Thorvald Hansen.

In the manufacture of automobile frames, the side bars and cross bars which are permanently united to constitute the structural unit of the frame, are formed from sheet metal blanks, which are punched from metal strips or plates, and which have their side marginal portions turned so as to stand normal to the plane of the body of the blank, and thus form a reinforced flanged channel bar. The engineering construction of many automobiles necessitates the use of curved side bars and cross bars in the frame unit, and serious mechanical difficulties have been encountered in producing such curved side and cross bars, in the particular forms prescribed by the designers of the automobile. These difficulties arise from the fact that in the drawing operation, by which the side margins of the blank are turned so as to constitute the upstanding flanges, the edge or border of the metal embraced within the

area of the concave flanged portion of the bar is required to be materially stretched or elongated, to accommodate it to the lengthened lines of the upturned flange at such concave curved portions. In such drawing operation, the stress imposed upon the metal within the area of the curved concave flange is very great, and such stress frequently results in the tearing of the flange at that point, so as to render the curved bar unserviceable, or so weakened as to create a liability to breakage of the bar at some later time, when a load is placed upon the structure.

We have discovered that the dies of the blanking press, in cutting through the metal of the strip or plate, produce a crystallization of the metal along the line of the action of the dies. The presence of such crystallization at the edges of the blank, creates a weakened condition, so that the metal at the edge of the blank in the concave portion yields quite readily under the strain imposed upon it in the drawing operation, in consequence of which the metal is sometimes torn, and if not torn, is so weakened as to be subject to the breakage adverted to.

For the purpose of overcoming the objection incident to the older practice of turning the concave margins of the blank, it has been the custom to subject the entire blank to an application of heat, whereby the crystalline structure is removed from the blank adjacent the cut edges, and the dies of the drawing press may turn the concave marginal portions of the blank without the adverse conditions usually resulting from the drawing operation. But the subjection of the whole of the blank to heat treatment is disadvantageous, inasmuch as the blank is thus softened in areas in which it is desirable that the original, rigid state of the metal, remain undisturbed.

We have found by extensive experiment and use that it is not necessary to anneal the whole of the blank, but that we may attain the results desired by merely locally annealing the blank in the area of the curved portions of the margin thereof. Such local annealing is effective to soften the metal of the blank in the desired degree with the result that the curved flanges may be turned or drawn without being subjected to the

strains incident to the practice of the older process. This local annealing we achieve with a very great economy in the use of the heat employed for that purpose, as compared 5 with the more recent process of annealing the whole of the blank, and at the same time, the initial rigid qualities of the major area of the blanks are preserved.

Our invention resides in an apparatus 10 which has been so constructed that the blanks are fed into the field of the heating elements, and permitted to remain within such field for a length of time sufficient to bring about the proper annealing of the 15 blanks in the concave edges thereof. The apparatus referred to is equipped with means which convey the blanks in a step-by-step movement, so that each blank is permitted to remain within the range of 20 the heat for a length of time which is approximately equal to that required to impart the step-by-step feeding movement to the series of blanks. The particular apparatus illustrated and hereinafter described 25 constitutes merely one form of device whereby our improved process of feeding the blanks in timed relation to the action of the heating elements may be carried out.

The novel features of our invention will 30 be recited in the claims appended to this specification.

In the drawings which accompany and form part of this application,

Figure 1 is a plan view showing our 35 newly devised apparatus for presenting the blanks in a position for the local annealing hereinbefore referred to, and showing also the arrangement of the device by means of which the heat treatment is applied to the 40 concave marginal portions of the blank.

Fig. 2 is a view in side elevation of the apparatus shown in Fig. 1, looking toward the latter figure.

Fig. 3 is an enlarged sectional view showing a portion of the metal blank and illustrating the manner in which the heat is applied.

In the drawings, the numeral 10 designates a pair of rails which may be supported by any suitable means, preferably in 50 a horizontal position. The sheet metal blanks A, which are to be subjected to heat treatment, are designed to be moved along the upper surfaces of the rails 10, and to be supported by the said rails in such movement.

A longitudinally reciprocating frame 11, located conveniently beneath the supporting rails 10, may be moved within a limited 60 traverse by any suitable mechanism. In the field, and adjacent one extreme of the reciprocating movement of the frame 11, a series of gas burners 12 is arranged. These gas burners 12 are connected with and sup-

ported by a supply pipe 13. The number 65 and location of the gas burners 12, will be such that the flame directed by them will be thrown against the concave portions of the margins of the blank A, when the latter has been moved to its most advanced or 70 forward position under one reciprocation of the slide 11.

The slide 11 is provided with a series of pairs of uniformly spaced upstanding arms 14, upon the upper end of each of which 75 a finger 15 is pivoted, as at 16. The number of pairs of arms 14, with complementary fingers 15, will be such as constitute a conveyor sufficient in length to carry the blanks in step-by-step movements through the apparatus. Each of the pivoted fingers 15 is provided with a counter-balance 17, which serves to maintain the finger 15 in an approximately vertical position, with the upper end of such fingers in engagement with 80 a stop 18, formed at the upper end of the arm 14, and extending across and at one side of the path of oscillation of the fingers 15. The said stop acts to limit the movement of the fingers 15 in one direction, as 85 will be clearly understood from an inspection of the drawing hereunto attached.

At its upper end, each finger 15 may be notched as at 19 for engagement with the rear edge of the blank, such notch lying 95 normally in the plane of the upper surface of the rails 10, above which the tips of the fingers 15 project slightly. But the notches 19 in the tips of the fingers 15, are not essential to the successful operation of the 100 apparatus, and may be omitted as a structural feature, if desired.

In the operation of our improved apparatus, the blanks A, placed upon the slide 11, are fed in spaced relation by a step-by-step movement in the reciprocations of the 105 said slide. This forward feeding movement of the blanks is due to the engagement of the projecting tips of the fingers 15, with the rear edge of the blank A, and the reciprocations of the slide 11 will carry the 110 said blanks successively into a position of rest, adjacent the gas burners 12. With the retirement of one set of fingers 15, after thus positioning one of the blanks A, the 115 reciprocation of the slide 11 will bring the next leading or forward set of fingers 15 at the rear of the gas burners and position them behind the blank A, which had been previously placed within the field of action 120 of the said gas burners. The pivotal arrangement of the fingers 15 upon the posts 14, will permit the said fingers to turn upon their pivots and pass under the blank A, previously positioned for heat treatment. 125 The counter-weights 17 automatically cause the tips of the fingers 15 to rise above the rails 10, and engage the rear edge of the

blank A, which has been subjected to heat treatment. In the succeeding movement of the slide 11, the treated blank A is carried forward a distance which is determined by 5 the extent of the reciprocation of the slide 11. This forward movement of the slide 11 to remove the treated blank A, also acts to position another blank for treatment, in a manner which will be understood from 10 what has been stated in the foregoing.

In the intervals of the step-by-step movement of the blanks A, into and out of position for the application of the heat by means of the gas burners 12, it is desirable, for reasons of economy, that the effective flame of the gas burners be reduced. This result we achieve by providing automatic devices for controlling the flow of gas, and reducing the pressure of the latter during the intervals of the movement of the blanks A over 20 the rails 10. The said devices are constituted of a plate 20, which is attached to the slide 11. The said plate 20 is provided with a slot 21, in which travels a pin 22, projecting from an arm 23, which latter has a loose connection, formed as a slot 24, embracing the flattened sides of the stem 25, of a valve or cut-off 26, coupled into the gas supply pipe 13.

30 In the movement of the slide 11 to the right, as indicated by the full-line arrow in Fig. 2, the pin 22 on the arm 23 will reach the end of the slot 21, which movement of the parts will rotate the stem of the valve, 35 to open the latter and permit the gas flame to play upon the concave marginal portions of the blank A, at the moment that the latter has been moved into its effective position. The gas will continue to flow during 40 the reverse movement of the slide 11 to the left as indicated by the dotted arrow in Fig. 2, and the full flame will be maintained until the pin 22 reaches the right hand end of the slot 21, in the continuing movement 45 of the slide 11 to the left. This last movement will rotate the stem 25 of the valve in a reverse direction and cut off the supply of gas, so as to reduce the flame to a minimum. The movement of the slide 11 to the 50 right again takes place, and in such movement the blank A which has been heat treated will be removed from its position in proximity to the gas burners, and a fresh blank will be positioned. At this moment, 55 the gas will again be turned on, and the newly positioned blank A be subjected to treatment, as before.

Fig. 3 illustrates somewhat more clearly 60 the manner of the application of the heat to the concave portions of the edge of the blank. The effect of the application of heat to such concave portions, is to destroy the crystalline formation in the edge of the blank, and thus counteract the liability of

the concave marginal portions of the blank 65 to tear when subjected to the drawing operation, by reason of the weakness of the metal due to the presence of crystallization created in the blanking operation.

The actuating means for reciprocating 70 the slide 11, will be so timed in its operation that the blanks which are to be heat treated will be intermittently advanced in a regular spaced procession to position with each blank in succession in the field of the gas 75 burners, and be allowed to remain at rest in such position for the action of the flame thereon for a given length of time, which will be predetermined as sufficient to enable the proper heating of the blank to be effected. The time allotted for the heating of the metal blanks will be approximately one-half of the cycle of operation of the apparatus, the other half of the said cycle being consumed in the step-by-step feeding movement of the succession of blanks.

While we have disclosed an apparatus in which the heaters occupy a relatively fixed position, and the blanks to be treated are passed with an intermitting movement 90 through the heating field, it will be within the scope of our invention to construct the annealing apparatus so that the metal plates or blanks will be fed in a continuous procession, and to arrange the heaters so as to 95 move with the blanks for a distance sufficient to permit a proper amount of heat to be applied to the blanks while in transit. In other words, the heaters may be caused to reciprocate along the path of movement of 100 the blanks, and while traveling therewith for a time, participate in such movement, for the attainment of the purposes of our invention.

The character of the gas used, its pressure, 105 and the extent of time during which the flame will be maintained, are factors to be determined by the structure of the particular blanks which it is desired to treat. Such adjustments as are necessary to secure 110 efficient results, may be made readily by any person skilled in the art to which the present invention appertains.

Having thus described our invention, what we claim and desire to secure by Letters Patent of the United States, is:

1. The method of locally annealing, which consists in the arrangement of heaters in a field, intermittently feeding a succession of metal plates in spaced procession into the 120 heating field, wherein each plate is subjected to action by the heat in the areas to be annealed, during the intervals of the intermitting feeding movements.

2. The method of locally annealing metal plates, which consists in intermittently feeding a succession of metal plates in spaced procession through a heating field, and

- singly subjecting the plates to action by the heat in the areas to be annealed while in such field and during the intervals of the intermittent feeding movements.
5. 3. The method of locally annealing, which consists in establishing a heating field, feeding a plurality of spaced metal plates in step-by-step movements into the heating field, subjecting the plates in succession to 10 action by the heat in the areas to be annealed while in such field in the intervals of the feeding movements of the plates, and reducing the volume of heat during such movements.
15. 4. The method of locally annealing, which consists in supporting a plurality of spaced and aligned heaters, intermittently feeding a succession of metal plates for action thereon by the heaters to anneal the said plates 20 in areas contiguous to the heaters in the intervals of the feeding movements of the plates, and controlling the volume of heat in the movement of the plates.
5. Apparatus for annealing local areas in 25 metal plates, comprising a series of heaters and means for intermittently feeding metal plates in spaced succession into the field of the heaters for action thereon in the intervals of the feeding movements.
30. 6. Apparatus for annealing local areas in metal plates, said apparatus comprising means adapted to maintain a heating field in which the metal plates are successively positioned for action by said heating means, 35 and intermittently operating means for moving the plates into and out of position in the heating field.
7. In an apparatus for annealing local areas in metal plates, a series of gas burners, 40 means for intermittently moving a succession of plates into the field of the said burners, and means operative in the movement of the plates to control the flow of gas to the burners.
45. 8. In an apparatus for annealing local areas in metal plates, the combination of a gas burner, with means for feeding a metal plate into the field of the burner, and connections from said feeding means operative 50 to control the flow of gas to the said burner.
55. 9. In an apparatus for annealing local areas in metal plates, the combination of a stationary gas burner, with automatic intermittently operating means for positioning a metal plate in the field of the burner and for removing the said plate from such field after treatment.
60. 10. In an apparatus for annealing local areas in metal plates, the combination of a gas burner, with a reciprocating slide adapted to feed a metal plate into and out of the field of action of the said burner, and connections whereby the said slide at the conclusion of its plate feeding movement acts to 65 turn on the supply of gas and at the conclusion of its reverse movement to reduce the flow of the gas.
11. In an apparatus for annealing local areas in metal plates, a support for the metal plates to be heat treated, a gas burner arranged in the path of movement of the plates over their support, and means for intermittently moving the plates in spaced succession into and out of the heating field. 70
12. In an apparatus for annealing local areas in metal plates, a support over which the plates to be heat treated are moved, a gas heater arranged in the path of forward movement of the plates, means for moving the metal plates over their support and into the field of action of the heater, and connections from said moving means whereby the flow of gas is turned on at the conclusion of the forward movement of the plate. 75
13. In an apparatus for annealing local areas in metal plates, a gas supply comprising a series of aligned burners arranged in the path of the forward movement of the plates to be heat treated, feeding means to position the plates in succession in the heating field, and connections from said feeding means operative to maintain the gas flame while the said plates are positioned as aforesaid, and to reduce the flame when the plates are removed from the said field. 80
- 90
- 95
14. In an apparatus for annealing local areas in metal plates, a gas supply comprising stationary burners, a fixed support over which the metal plates to be heat treated may be moved, and means for moving the plates over the support in spaced succession and positioning them in the field of action of the burners.
15. In an apparatus for annealing local areas in metal plates, a gas supply comprising stationary burners, a support over which the metal plates to be heat treated may be moved, means for moving the plates, and connections from the said means adapted to control the flow of gas to the burners. 100
- 105
- 110
- 115
- 120
16. In an apparatus for annealing local areas in metal plates, a support for the plates to be heat treated, a gas heater in fixed conjunction with the said support, a valve controlling the flow of gas to the heater, means for moving the plates on the support and positioning them in the field of action of the gas burner, and connections between the said means and the valve, whereby the flow of gas is caused to rise when the plates are moved into effective relation to the heater.
- In testimony whereof, we have signed our names at Milwaukee, this 7th day of October, 1920.
